his attorney
O. Riley Edwards

UNITED STATES PATENT OFFICE.

GEORGE SEIFFERT, OF NEW YORK, N. Y., ASSIGNOR TO ELECTONE COMPANY, INC., OF NEW YORK, N. Y., A CORPORATION OF DELAWARE.

PHONOGRAPH.

Application filed December 9, 1919, Serial No. 343,474. Renewed November 2, 1923.

To all whom it may concern:

Be it known that I, GEORGE SEIFFERT, a resident of the city of New York, county of New York and State of New York, have invented a new and useful Improvement in Phonographs, of which the following is a specification.

The object of this invention is to provide a sound box which operates upon compressed air which is regulated in such a manner that the sound or music recorded in a record may be faithfully reproduced with any desired loudness according to the adjustment of the apparatus.

15 This and other objects are accomplished by my invention, one embodiment of which is hereinafter more particularly set forth.

For a more detailed description of my invention, reference is to be had to the accompanying drawings, forming a part hereof, in which—

Figure 1 is a side elevation of a part of a phonograph embodying my invention.

Figure 2 is a plan view of the sound box, tone arm and air pressure pipe of the same.

Figure 3 is an end elevation of the structure shown in Figure 2.

Figure 4 shows the interior of the sound box when the cover is removed.

30 Figure 5 is an enlarged section taken on the line 5—5' of Figure 1, looking in the direction of the arrows.

Figures 6 and 7 are sections taken on the lines 6—6 and 7—7 respectively of Figure 5, looking in the direction of the arrows.

Figure 8 is a sectional view, taken on the line 8—8 of Figure 7, looking in the direction of the arrows.

Figure 9 shows a fixed grate surface of the sound box.

Throughout the various views of the drawings, similar reference characters designate similar parts.

My improved phonograph 1 is provided 45 with the conventional turn table 2 on which is placed a record 3, in the conventional manner, which record has its groove engaged by a needle 4 fixed in a needle holder 5 by the usual set screw 6. The needle holder 5

50 is secured to the sound box 7, and this sound box has a lower connection with the tone arm 8 and an upper connection with the compressed air pipe 9. This tone arm 8 and the compressed air pipe 9 always move with

the sound box 7 and swing with the same 55 over the record 3.

The needle holder 5 has a spring 10 secured rigidly thereto by a suitable holding means as brazing or welding and this spring has a laterally extending tongue 11 at its 60 center and laterally extending ends 12 which are parallel to the tongue at the center, but extend only a short distance, as shown in Figure 8. This spring 10 also has seats 13 for the fixed fulcrums, as will appear below. 65 The ends 12 are held under suitable caps 14 which are secured to the bottom of the sound box 7 by cap screws 15 which hold these parts rigidly in place.

In the preferred embodiment of my invention, the screws 15 take into suitable downwardly extending lugs 16 which are formed for the purpose and between which is placed a grating 17, which is made of polished metal such as German silver. The 70 needle holder 5 has an upwardly extending tapering plate 18 which is also provided with a grating 19 which is identical with the grating 17 except that the openings of one register with the bars of the other so that 75 when the two are placed together, as shown in Figure 7, there will be no openings through which air can issue.

It will be noted that the seats 13 of the spring 10 receive the fulcrum points 20 of 80 the sound box 7, and that, as shown in Figure 5, the projection 11 of the spring 10 extends laterally far enough to take under a screw 21 which rests in a sieve 22 that runs across the sound box 7 and which may be 85 turned by means of a screw driver so as to regulate the tension on the spring 11. As long as the parts 17 and 19 are kept together under the tension of the spring 11, no sound or music can issue from the sound box 7, but 90 when these parts are separated under the influence of the needle 4 in the record 3, there is more or less opening between these gratings and then a corresponding musical note or sound will issue according to what is on 95 the record.

If the gratings 17 and 19 be made of the same material, I have found that they will not function properly and that it is essential for good operation of the instrument that 100 these gratings be of different materials. The best results I have obtained have been obtained with a grating 17 made of German

silver and a grating 19 made of aluminum. Both of these gratings are highly polished so as to form a tight joint together, as above described.

5 In the preferred embodiment of my invention the grating 17 is held in a plate 23 which in turn is placed between two rubber gaskets 24 and 25 and joined by screws 26 which run from the interior of the sound 10 box 7 and through the gaskets 24 and 25 and plate 23 to a boss 27 to which the tone arm 8 is secured by a sliding fit in the conventional manner. The upper part of the sound 15 box 7 is provided with an integral boss 28 which is screw threaded on its exterior to receive a union 29 which secures the air pipe 9 in the conventional manner. The upper part of the grating 17 may be further secured by suitable screws 30 and it is preferable to provide the interior of the sound 20 box 7 between the air pipe 9 and the tone arm 8 with a filtering screen 31 which will prevent dust from getting at the gratings 17 and 19 and interfering with their action.

25 It will be noted that the upper extension 18 of the needle holder 5 projects through a corresponding opening in the boss 27 so that this needle holder may swing at its fulcrums 20, to any desired extent, without having any contact with the boss. In the embodiment of my invention here illustrated the needle point takes a zig-zag course.

The sound box 7, on its front, is provided with a screw cap 32 which has an interior 25 lining 33 of rubber or similar material to act as a cushion and to facilitate the formation of a tight joint so that air passing through the sound box will neither leak nor make a noise.

30 In view of the foregoing, the operation of my improved instrument will be readily understood. Assuming that the sound box is as shown and that a record 3 is revolving on the table 2 and imparting the usual movement to the needle 4, the gratings 17 and 19 will approach and separate according to the irregularities of the record and as they approach or separate, air under pressure passes through the sound box 7 and at the 35 gratings sounds the note or music of the record and faithfully reproduces the same.

The loudness with which this reproduction takes place will depend on the pressure of the air in the pipe 9 and the tension of the spring 11 under the influence of the screw 55 21. By changing either or both of these factors, the loudness of the music or noise in the tone arm may be correspondingly changed.

60 While I have shown and described one embodiment of my invention, it is obvious that it is not restricted thereto, but that it is broad enough to cover all structures that come within the scope of the annexed claims.

Having thus described my invention what I claim is:

65 1. A sound box having an air pipe at its top and a tone arm at its bottom, a German silver grating rigidly secured to the sound box and an aluminum grating adjacent to the other grating and mounted so as to vibrate according to a record.

70 2. A sound box of the class specified having a fixed grating of German silver and a movable tapering grating of aluminum and means for causing the movable grating to vibrate according to a record.

75 3. A sound box of the class specified having a fixed grating of German silver and a movable grating of different material and means for causing the movable grating to vibrate according to a record.

80 4. A sound box of the class specified having a fixed grating of a material which will not change under atmospheric conditions and a movable grating of a different material which will not change under atmospheric conditions and means for causing the movable grating to vibrate according to a record.

85 5. A sound box of the class specified having a fixed grating of German silver and a movable grating of a different material which will not change under atmospheric conditions and means for causing the movable grating to vibrate according to a record.

90 6. A sound box of the class specified having two gratings, one of German silver and the other of aluminum and means for causing one of said gratings to vibrate according to a record.

95 GEORGE SEIFFERT.
